UNITED STATES PATENT OFFICE.

JOHN B. HOAGLAND, OF ST. LOUIS, MISSOURI, ASSIGNOR OF ONE-HALF TO THEODORE B. AUFRICHT, OF ST. LOUIS, MISSOURI.

SCREEN.

974,380.

Specification of Letters Patent.

Patented Nov. 1, 1910.

Application filed April 12, 1909. Serial No. 489,329.

To all whom it may concern:

Be it known that I, JOHN B. HOAGLAND, a citizen of the United States, residing at St. Louis, in the State of Missouri, have invented a new and useful Screen, of which the following is a specification.

This invention relates more particularly to the frame of the screen, and its object is to provide an improved joint for the corners thereof.

The invention also has for its object to provide a joint by which the frame sections can be readily assembled by unskilled persons.

Another object is to provide a joint which is strong and which results in a rigid frame. With the foregoing objects in view the invention consists in a novel construction and arrangement of parts to be hereinafter described and claimed, reference being had to the drawing hereto annexed forming a part of this specification, in which drawings—

Figure 1 is a perspective view of a portion of the screen. Fig. 2 is a perspective view 25 of one of the corner fastenings removed.

In the drawing, 5 denotes the stiles, and 6 one of the rails of the screen frame. The outer edges of the stiles are grooved as usual to receive the slides. The wire cloth, or 30 other screen fabric or material which is indicated at 7, is secured to the frame by extending it at its edges into grooves 8 made in the face of the stiles and rails, and in which grooves it is held by strips 9 driven 35 thereinto, the screen being thus securely held between the strips and the walls of the grooves. In making the frame, it can be either mitered, or cut square at the corners so as to bring the grooves together.

The screen frame herein described is of 40 that type known as a knock-down frame, the stiles and rails being fastened together by corner fastenings which will now be described.

The corner fastening comprises a sheet metal plate consisting of two branches 10 and 11, respectively, extending at right angles to each other. A plate as herein described is fastened to each corner of the 50 frame by means of nails, brads or other suitable fastening means 12. The branch 10 is secured to the rail, and the branch 11 to the adjacent stile, the width of said branches being slightly less than the width of the

rail and stile, so as to permit the latter to 55 be trimmed to properly fit the window or other frame. Each branch of the plate is formed with a bead 13 made by bending the plate, which beads extend into the grooves 8, the bead of the branch 10 fitting in the 60 groove of the rail, and the bead of the branch 11 fitting in the groove of the stile. The beads clamp the corners of the screen fabric in the same manner as the strips 9. The strips, however, may be continued 65 through the channels formed by the beads so that the appearance of the frame may not be marred.

At the inner edge of the corner plate is a flange which fits the inner angle of the 70 frame. This flange extends at right angles to the corner plate and is formed on each branch thereof, both portions of the flange being indicated at 14 in the drawings. In the flange are made a number of openings 75 15 through which the nails, brads or other fastening devices are adapted to be driven into the frame.

By means of the corner fastening herein described, the stiles and rails can be readily 80 assembled and fastened together, and they will hold the frame square and rigid. The corner fastening is preferably made of a single piece of sheet metal which is stamped into the shape shown, in view of which it 85 can be cheaply produced.

The bead 13 not only secures the corners of the screen fabric, but also serves to stiffen the plate, and to assist in holding it in place.

What is claimed is:

The combination with a wooden screen frame having a grooved face, of a corner fastening comprising an angular sheet metal plate fitting the frame at the corners thereof, and spaced at its outer edge from the outer edge of the frame to permit trimming of said edge, said plate having a bead entering the groove of the frame, and a flange projecting from the inner edge of the plate at an angle thereto, said flange 100 fitting in the inner angle of the frame.

In testimony that I claim the foregoing as my own, I have hereto affixed my signature in the presence of two witnesses.

JOHN B. HOAGLAND.
